UNITED STATES PATENT OFFICE.

THOMAS KENNEDY, OF PHILADELPHIA, PENNSYLVANIA.

STOPPER FOR FRUIT-JARS, &c.

SPECIFICATION forming part of Letters Patent No. 320,364, dated June 16, 1885.

Application filed January 12, 1885. (No model.)

To all whom it may concern:

Be it known that I, THOMAS KENNEDY, a citizen of the United States, and a resident of Philadelphia, Pennsylvania, have invented 5 certain Improvements in Stoppers for Fruit-Jars and other Vessels, of which the following is a specification.

My invention consists of certain improvements in the construction of devices for closing 10 the mouths of fruit-jars and other vessels in which oblong stoppers are adapted to corresponding seats inside the mouths of the vessels, as fully described and claimed herein-after.

15 In the accompanying drawings, Figure 1 is a vertical section of a fruit-jar with my improvement. Fig. 2 is a plan view of the same, showing the manner of inserting the stopper. Fig. 3 is a perspective view. Fig. 4 is another perspective view, showing the application of my invention to a kettle. Fig. 5 is a perspective view of a retaining-bar, and Fig. 6 is a view of a modification of the same.

A is the body of the jar or other vessel, 25 which is provided with a mouth, B, flanged or beveled, as shown in Fig. 1, to form an inside bearing for the stopper D. The mouth of the vessel has an interior outline of an oval or other oblong shape, as shown in Fig. 2, and 30 the stopper is correspondingly shaped, and is provided around its periphery with a rubber or other gasket, d. The upper face of the stopper is provided with a hook or eye, E, through which can be passed the spring retaining-bar F, whose opposite ends are to rest 35 on the upper edges of the mouth of the vessel. This retaining-bar is of the construction shown in Figs. 1 and 5—that is, arched or bent to form in effect an elliptic spring, and having at 40 one end an enlargement or flattened head, f, and at the other end a hook, f', which catches the eye E when the retainer is drawn out from engagement with the upper edges of the mouth of the vessel, and affords a means of 45 handling the stopper to insert or withdraw it, as illustrated in Fig. 2. This hook f' may be at right angles with the flattened head f, as shown in Figs. 1, 2, and 3; but I prefer to make it about parallel therewith, as shown in Figs. 5 50 and 6, so as to leave no unnecessary projection when the vessel is closed. In the modified form shown in Fig. 6 the hook is extended to form a closed loop, so that the retaining-bar will at all times remain connected with the

stopper and not get separated therefrom and 55 lost. In applying the stopper the hooked retainer F is passed through the eye of the stopper and the latter is inserted into the mouth of the vessel, as shown in Fig. 2, and then turned so that the oblongs of the stopper 60 and mouth will coincide. Then the retainer F is brought to a horizontal position and moved laterally until its opposite ends rest on the upper edges of the mouth of the vessel with the elasticity of the bar tending to pull 65 the stopper upward to a tight closure to its seat. In Fig. 5 the bar is shown in its normal curved form when free, while in Fig. 1 it is shown constrained. The precise curve or bend or shape of the bar is not material, how- 70 ever, so long as it has some inherent elasticity. In the modification, Fig. 3, the bar is inserted in the position shown, and then turned, as indicated by the arrow, up onto the notched projections b, which will bring the desired 75 strain on the retainer. If the retainer should at any time get out of shape, it can readily be bent again to the necessary form. The flattened head f at one end of the retainer, and in some cases also the hook f' at the other, 80 prevents the retainer from being turned under constraint.

My invention, it will be understood, can be applied to various forms of vessels as well as fruit-jars. For instance, I have shown it ap- 85 plied to a butter kettle or keg in Fig. 4, in a manner which will be readily understood without explanation.

I claim as my invention—

1. A vessel having an oblong inside seat 90 and corresponding stopper with an eye, in combination with an upwardly-curved spring-retainer passing through the eye, and having a flattened head to rest on the mouth of the vessel, substantially as and for the purpose 95 set forth.

2. A vessel having an oblong inside seat and an oblong stopper provided with an eye, in combination with a spring retaining-bar having a closed loop adapted to said eye, sub- 100 stantially as set forth.

In testimony whereof I have signed my name to this specification in the presence of two subscribing witnesses.

TH. KENNEDY.
